UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,558, dated January 7, 1890.

Application filed December 9, 1889. Serial No. 833,152. Term of patent 3½ years.

To all whom it may concern:

Be it known that I, WILLIAM K. BENEDICT, of the city, county, and State of New York, have invented and produced a new and original Design for the Exterior of a Residence, of which the following is a specification, reference being had to the accompanying drawings, forming a part thereof.

Figure 1 represents a perspective view of a residence showing my design. Fig. 2 represents a horizontal section or plan of the first story. Fig. 3 represents a horizontal section or plan of the second story.

Similar letters of reference designate corresponding parts in all the figures.

A residence embodying my design is generally rectangular on the ground plan, and comprises a first and second story and an attic, the whole being surmounted by gable roofs. The front A of the first story is substantially flat. At one side of the front A, and extending around for a distance upon the side, is a porch B. The side C of the first

story has a projecting portion a, and upon the portion a is shown an oriel bay D. The second story has a substantially flat portion E at the front and a substantially flat portion F at one side. To the rear of the portion F is a projecting portion G, which overhangs the portion a of the first story. Between the portion a and the portion G are cantilevers b. The portions E F are surmounted by a gable roof H, which extends downwardly to the top of the second story. The portion G is surmounted by a gable roof I, extending at about right angles to the roof H. The roof I does not extend downwardly quite so far as does the roof H.

What I claim is—

The design for the exterior of a residence, substantially as herein shown and described.

WILLIAM K. BENEDICT.
